 F. B. Redington Co, Chicago, Ill., a corporation
 of Illinois

Application September 15, 1941, Serial No. 410,811

9 Claims. (Cl. 198—131)

This invention relates to conveyer structures, particularly of the type adapted for use with packaging machines or the like.

It is an object of the invention to provide an improved conveyer structure for conveying articles, packages and the like, wherein the conveyer pockets or buckets are adjustable to accommodate various size articles or packages.

More specifically stated, it is an object of the invention to provide a conveyer having adjustable pockets or buckets wherein the pockets give complete support to the articles or packages being conveyed, in all adjusted positions of the pockets.

A further object of the invention is to provide a conveyer structure having adjustable pockets or buckets, wherein the adjustable pocket parts are at all times maintained in proper relative positions, the parts themselves being shaped and cooperating to maintain their proper predetermined positions.

A still further object of the invention is to provide a conveyer structure having adjustable pockets, wherein the pocket parts provide complete support for the articles or packages to be conveyed, while at the same time permitting the ready loading and emptying of the pockets, and also the necessary movement of the conveyer parts as they are transmitted over operating sprockets and the like.

Various other objects, advantages and features of the invention will be apparent from the following specification when taken in connection with the accompanying drawings wherein one preferred embodiment of the invention is set forth for purposes of illustration.

In the drawings, wherein like reference numerals refer to like parts throughout:

Fig. 1 is a partial plan view of a conveyer structure constructed in accordance with and embodying the principles of the invention;

Fig. 2 is a longitudinal sectional view through the structure of Fig. 1, on the line 2—2 thereof, and more particularly illustrating the conveyer pocket or bucket construction;

Fig. 3 is a view similar to Fig. 2, but showing the conveyer pockets as adjusted to receive larger articles or packages;

Figs. 4 and 5 are detail perspective views of the cooperating conveyer pocket parts;

Fig. 6 is a longitudinal sectional view through the conveyer structure, on the line 6—6 of Fig. 7; and

Fig. 7 is a transverse sectional view through the structure on the line 7—7 of Fig. 6.

Referring more particularly to the drawings, and first to Fig. 1, it will be seen that the structure illustrated comprises an article or package conveyer, generally indicated by the numeral 10, and an operating mechanism associated therewith, indicated by the numeral 11. The conveyer structure and the operating mechanism are illustrated as being of the type adapted for use with packaging machines and the like, and they 5 may comprise a part of a complete packaging machine. For clarity of illustration only a part of the conveyer and its associated structure are shown.

The conveyer comprises more specifically two 15 reaches or sections 12 and 13, in the form of endless chains; and adapted upon operation to transmit a series of conveyer pockets 14 for receiving articles, packages or the like 15, along a predetermined path as indicated by the arrow in Fig. 1.

20 The conveyer sections 12 and 13 operatively engage and are driven by sprockets 16 and 17, respectively, which sprockets are in turn adapted to be driven from a drive shaft 18 by means later to be described. In addition to the driving 25 sprockets 16 and 17, the conveyer sections or chains also pass over idler sprockets (not shown) at the opposite end of the conveyer structure, as may be readily understood by those skilled in the art.

30 The conveyer section 12 comprises a series of main links 19, Figs. 1 and 2, and a series of connecting links 20, alternately arranged, and connected by pivot pins 21 whereby to form an endless chain construction. Similarly, the conveyer section 13 comprises a series of main links 22, Figs. 1 and 6, and alternately arranged connecting links 23, pivotally connected together by means of pivot pins 24. As will be best understood by reference to Figs. 4 and 5, the main links 22 of the conveyer section 13 are integral 35 with and formed as a part of members 25 which constitute the principal elements of the conveyer pockets. Similarly, the main links 19 of the conveyer section 12 are integral with and formed 40 as a part of members 26 constituting the cooperating elements of the conveyer pocket structures, members 25 and 26 forming the complete conveyer pockets. It will thus be seen that the endless chains which constitute the operating conveyer sections 12 and 13 in part are formed by 45 the conveyer pockets themselves, so that only the auxiliary or connecting links 20 and 23, and their associated pivot pins, need be provided to form the endless conveyer chains.

50 55 The means for driving the sprockets 16 and 17

from the drive shaft 18 is best illustrated in Figs. 6 and 7 and will now be described. A collar 30 is pinned to the drive shaft 18 by suitable means such as the pin 31, Fig. 7. This collar is provided with a series of arcuate slots 32, three in number in the particular embodiment illustrated, which slots are adapted to adjustably receive clamping bolts 33. The bolts 33 are threadedly anchored to another collar 34 loosely mounted on the shaft 18, which latter collar is fixed to the sprocket 17 by means of a series of bolts 35. It will be seen that by loosening of the bolts 33, the collar 34 and the associated sprocket wheel 17 may be adjusted relative to the collar 30 and the driving shaft 18, through a maximum distance determined by the length of the slots 32. Upon retightening of the bolts the parts will be held in the adjusted position, and to facilitate the adjustment, collars 30 and 34 may be provided with circumferentially spaced 20 wrench-receiving openings 36, as indicated in dotted lines in Fig. 6.

The driving connection between the sprocket 16 and the drive shaft 18 may be of similar character and preferably includes a collar 40 pinned to the drive shaft by means of a pin 41, the collar being provided with arcuate slots 42 as in the case of the collar 30. Bolts 43 are adjustably received within these slots, the bolts being anchored to a collar 44 rotatably mounted on the shaft 18, and secured to the sprocket 16 by means of bolts 45. Upon release of the bolts 43 the sprocket 16 and its associated rotatably mounted collar 44 may be adjusted with respect to the collar 40 and the drive shaft 18, as previously described. It will thus be seen that by means of the connections provided sprockets 16 and 17 are independently adjustable, through predetermined limits, with respect to the drive shaft 18. It is to be understood that the drive shaft 18 is driven by suitable power connections, in timed relation with the operation of the other parts of the machine.

The purpose of the adjustment means for the sprockets 16 and 17 is to permit the adjustment of the conveyer pockets to receive different size articles or packages, and the action will be best understood by a comparison of Figs. 2 and 3. Thus, in Fig. 2 it will be seen that the pockets 14 are adjusted to receive packages of a predetermined smaller size, whereas in Fig. 3 the pockets are adjusted to receive packages of a predetermined larger size. More particularly, as the sprockets 16 and 17 are adjusted relative to each other, the conveyer chain sections 12 and 13 are relatively adjusted whereby to move the pocket members 25 and 26 relatively closer together or farther apart as the case may be, and as may be desired to accommodate a particular size of package or article. As the sprocket 16 is shifted clockwise relative to the sprocket 17, as seen in Fig. 6, pocket members 26 are moved to the right relative to pocket members 25 whereby to open or enlarge the pocket structures.

The details of the pocket forming elements are best shown in Figs. 4 and 5, and it will be seen that the pocket structures are so formed that they provide complete support for the articles or packages, in all adjusted positions. More particularly, the principal pocket element or member 25 is of generally angular shape and is provided with an upstanding wall portion 50, forming the rear or trailing pocket wall, and a bottom or platform portion 51 upon which the

packages or articles are received. The platform portion is provided with a downwardly sloped beveled front edge 52, and also with two cutouts or openings 53 and 54. The cooperating pocket member 26 is formed with an upstanding wall 55 forming the leading or forward pocket wall portion, and this wall is provided at its lower edge with a beveled surface 56, as also shown in Figs. 2, 3 and 6. Extending forwardly from the wall 55 are two abutment projections 57 and 58, these projections being in alinement, respectively, with the notches or cut-away sections 53 and 54 of the pocket member 25.

As previously stated, the pocket members 25 and 26 form a complete support for the conveyed articles on at least three surfaces thereof, such support being provided in all the adjusted positions of the pockets, for example as shown in Figs. 2 and 3. More particularly, it will be noted that when the pocket members are in operative position, the platform portion 51 of the principal pocket element extends underneath the wall 55 of the pocket member 26, so that regardless of the adjustment of the parts a complete bottom support for the articles or packages is provided.

The projections 57 and 58, in cooperation with the cutouts 53 and 54 insure the maintenance of the parts in proper alinement in all adjusted positions. To this end it will be seen that the projections and the cutouts interlock with each other, maintaining the pocket elements 25 and 26 in proper relative position at all times, whether during operation of the conveyer, or during the adjustment thereof to change the pocket size. The cut-away portions 53 and 54 of the principal pocket element in effect form a projection 60 engageable within a notch 61 formed in the wall surface of the cooperating pocket member 26. Projections 57 and 58 also provide abutment surfaces for limiting the minimum size adjustment of the pocket structures.

While the pocket elements form a complete bottom support for the articles or packages being conveyed, at the same time the parts are so constructed and arranged as not to interfere with each other in the operative movement of the structure. More particularly, the beveled surface 56 of the pocket member 26 permits the latter to undergo a free, clockwise, pivotal movement as the sprocket 16 is engaged, whereby to avoid any interference between the pocket parts. The action will be best understood by reference to Fig. 6 wherein it will be seen that the beveled surface 56 permits the clockwise pivoting of the pocket member 26 relative to pocket member 25 without interference.

Further, the tapered surface 52 of the pocket member 25 insures non-interference between the parts even when the pockets are adjusted to a maximum size. As the pocket members 25 engage the sprocket wheel 17, the forward or leading edge of the platform 51 assumes a circumferential path of travel which is radially spaced from the shaft 18 a somewhat greater distance than the path of travel assumed by the mid-portions of the platform, this action also being best illustrated in Fig. 6. When the pockets are adjusted to maximum size so that the vertical wall portions 55 of members 26 are in alinement with the forward edges of the platforms 51, interference would result were it not for the provision of the beveled surfaces 52. These surfaces insure that the pocket members 26 will not be thrust radially outwardly and improperly lifted from the sprock-

et wheel 16, even when the pockets are adjusted to maximum size.

Similarly, it will be noted that the links 19 are provided on their forward ends with tapered or beveled surfaces 63, Fig. 5. These surfaces provide clearance for the platforms 51 as the pocket members engage the sprockets and assume their arcuate path of travel. The tapered surface 63 on each member 26 underlies the portion 51a of the platform 51 on the member 25 just ahead. Interference between the parts in the operation of the structure is precluded, in all positions of pocket adjustment.

The particular operating mechanism 11 set forth for purposes of illustration, is of the type provided for ejecting the packages from the conveyer. It comprises a series of ejector members 65 operatively engageable with the ends of the packages for removing them from position within the article conveyer pockets. During operation of the structure the ejector members 65 are moved along the path of travel of the packages, and at the speed of travel of the packages, and at the same time are thrust into engagement with the package ends to effect the ejecting operation.

To effect the translation of the ejector members along the path of travel of the packages, as indicated by the arrow in Fig. 1, the members are mounted, respectively, in brackets 66 formed as a part of a conveyer structure 67. The main links 68 of this conveyer are formed on the bottoms of the brackets 66, and these links together with the connecting links 69 and pivot pins 70 make up an endless chain structure, as in the case of the conveyers 12 and 13. The conveyer is operated by a sprocket wheel 71 pinned to shaft 18 by a pin 72, Fig. 7.

The ejector members 65 are mounted for transverse reciprocation within the brackets 66, and to effect the movement of the ejector members into engagement with the ends of the packages, the members are provided with pins or rollers 73 engageable with a fixed frame cam 74 as the ejector members reach the station illustrated in Fig. 1. The adjustment means, heretofore described, for the sprockets 16 and 17 permits the article conveyer pockets 14 to be accurately aligned with the ejector members.

It is to be noted that the projections 57 and 58 of each pocket member 26 are sloped downwardly so as to insure a smooth bottom platform in the pocket for receiving the packages, thereby insuring smooth loading and unloading operations. The slope of the projections also permits the tilting of the pocket member 26 around its sprocket without lifting the package from the pocket member 25. In other words, the packages rest fully upon the platform portion 51 of the pocket member 25 which is of coplanar one-piece construction.

The operation of the structure is believed to be clear from the foregoing, but may be briefly summarized as follows: During operation, as the drive shaft 18 is rotated, sprockets 16, 17 and 71 are operated as a unit, causing the operation of the conveyers 12, 13 and 67. The packages or articles 15 are introduced into the conveyer pockets 14, either manually or automatically by means (not shown) arranged at another station of the packaging machine, and as the parts reach the position shown in Fig. 1 the rollers 73 of the ejector members 65 engage the stationary cam 74 whereby to eject the packages from the conveyer pockets.

The sprockets 16 and 17 may be adjusted rela-

tive to the drive shaft 18, so as to maintain accurate alignment with the ejector members, and also for the purpose of varying the size of the article-receiving pockets. The pockets, while so 5 adjustable, provide complete support for at least three sides of the packages, including a full bottom support; and the individual parts of the pockets are so constituted and arranged as to permit the proper movement of the conveyer elements in all positions of pocket adjustment. Additionally, the pocket parts are so interlocked and mutually guided that they are maintained at all times in proper relative positions.

It is obvious that various changes may be made in the specific embodiment of the invention set forth for purposes of illustration without departing from the spirit thereof. Accordingly, the invention is not to be limited to the embodiment shown and described, but only as indicated in the following claims.

The invention is hereby claimed as follows:

1. A conveyer comprising a series of article conveying pockets adapted to be moved along a predetermined path, each of said pockets being formed of a plurality of relatively adjustable parts whereby to provide pockets of variable size, and means for adjusting said parts, said parts being shaped to provide in all normal positions of adjustment complete support for the articles in at least three planes, said parts in said normal positions of adjustment having overlying portions substantially in contact and adapted for relative pivotal movement during the operation of the conveyer, and one of said parts being cut away to provide a substantially knife edge forming a pivot fulcrum between the parts.
2. A conveyer structure for packaging machines and the like comprising a first conveyer section, a second conveyer section, a first pocket member connected to the first conveyer section, a second pocket member connected to the second conveyer section, and means for adjusting the relative position of the conveyer sections whereby to adjust the relative position of the pocket members to provide pockets of different size, said pockets being of general trough shape and being provided at one longitudinal portion thereof with a bottom portion extending completely across the pocket in all normal positions of pocket adjustment, one of said pocket members being cut away to provide a substantially knife edge forming a pivot fulcrum between the pocket members.
3. A conveyer structure comprising a first conveyer section, a second conveyer section, a first pocket member connected to the first conveyer section, a second pocket member connected to the second conveyer section, means for adjusting the relative position of the conveyer sections whereby to adjust the relative position of the pocket members to provide pockets of different size, said pocket members having predetermined portions thereof in substantially operative contact in all normal positions of pocket adjustment, one of said portions being cut away to provide a substantially line contacting engagement in all said positions of adjustment, the pocket members being pivotal relative to each other about said line contact during operation of the conveyer.
4. A conveyer comprising a series of article conveying pockets adapted to be moved along a predetermined path, each of said pockets being formed of a pair of relatively adjustable parts whereby to provide pockets of variable size, and means for adjusting said parts, one of said parts being of general L-shape whereby to provide a

pocket bottom and a pocket side wall on one side thereof, and the other of said parts comprising a member in substantial abutting relation with the free end of the pocket bottom in all normal positions of pocket adjustment and adapted to form an opposed side wall for the pocket, one of said parts being cut away to provide a substantially knife edge forming a pivot fulcrum between the parts.

5. A conveyer comprising a series of article conveying pockets adapted to be moved along a predetermined path, each of said pockets being formed of a pair of relatively adjustable parts whereby to provide pockets of variable size, and means for adjusting said parts, one of said parts being of general L-shape whereby to provide a pocket bottom and a pocket side wall on one side thereof, and the other of said parts comprising a member in substantial abutting relation with the free end of the pocket bottom and adapted to form an opposed side wall for the pocket, the pocket bottom being tapered at the free end thereof to provide a bottom of decreasing thickness toward said free end.

6. A conveyer comprising a series of article conveying pockets adapted to be moved along a predetermined path, each of said pockets being formed of a pair of relatively adjustable parts whereby to provide pockets of variable size, and means for adjusting said parts, said parts being provided with interengageable elements adapted to remain in operative contact in all normal positions of pocket adjustment, and one of said elements being provided with a tapered surface whereby to maintain the pocket parts in predetermined relative position during the relative movement thereof on operation of the conveyer.

7. A conveyer comprising a series of article conveying pockets adapted to be moved along a predetermined path, each of said pockets being formed of a pair of relatively adjustable parts whereby to provide pockets of variable size, and

means for adjusting said parts, each of said parts being provided with a plurality of interengageable notches and projections adapted to remain in operative contact in all positions of pocket adjustment whereby to maintain the pocket parts in predetermined relative position, and certain of said projections being provided with tapered surfaces to provide a proper pocket structure on relative movement of the parts during operation of the conveyer.

8. A conveyer structure for packaging machines and the like comprising a first conveyer section, a second conveyer section, a first pocket member having integral links forming a longitudinal portion of the first conveyer section, and a second pocket member having integral links forming a longitudinal portion of the second conveyer section, the links of one of said pocket members projecting therefrom and being adapted to lie beneath the second pocket member during the operation of the conveyer, said last named links being provided with cut away relieved surfaces to accommodate the relative shifting of the pocket members during conveyer operation.

9. A conveyer comprising a series of article conveying pockets adapted to be moved along a predetermined path, each of said pockets being formed of a pair of relatively adjustable parts whereby to provide pockets of variable size, and means for adjusting said parts, one of said parts being of general L-shape whereby to provide a pocket bottom and a pocket side wall on one side thereof, and the other of said parts comprising a member in substantial abutting relation with the free end of the pocket bottom and adapted to form an opposed side wall for the pocket, the abutting portion of said last named member being provided with a substantially knife edge whereby to provide for the pivoting of said member relative to the pocket bottom during the operation of the conveyer.

CLARENCE J. MALHIOT.
